TYPESETTING MACHINE

Richard C. O'Brien, Huntington, N.Y., assignor to Harris-Intertype Corporation, Cleveland, Ohio, a corporation of Delaware

Filed June 11, 1965, Ser. No. 463,198
8 Claims. (Cl. 199—23)

This invention relates to typesetting machines of the recirculating matrix type, and particularly to a novel operating unit for controlling the functioning of the individual matrix release mechanisms in response to a coded input signal identifying, in succession, the matrices to be selected in making up lines of composition.

The recirculating matrix typesetting machines are provided with at least one mechanism having a number of channels in each of which a number of matrices are contained for release, one at a time, by suitable mechanisms associated with each channel. The selection signals may be derived from a keyboard, or from a coded input such as a perforated paper tape, but in either event these signals cause the release mechanisms to discharge a single selected matrix for each signal, and the matrices drop in the order of selection into a suitable assembler. The present invention is concerned primarily with an apparatus which can be controlled by the keyboard, or by a coded input from a perforated tape or the like, and which functions to operate the matrix release mechanism in the predetermined order, and at regular intervals despite possible irregularity in the rate of input of the signals, such that the individual matrices can be selected and released rapidly and regularly into the assembler.

In a preferred form of the invention this apparatus includes an electro-mechanical decoding mechanism which translates a coded input into an operating signal for the particular one of the matrix release mechanisms identified by that signal, and causes such mechanism to be actuated to release a single matrix. The rate of operation of this apparatus is fed back to control its input, whereby the decoding mechanism accepts the input coded signals at regular intervals, then proceeds to decode and actuate the proper matrix release mechanism. The actual decoding and selection function is arranged to be only a part of the actuating output of the apparatus, such that the apparatus can prepare to accept the next signal while the output resulting from the previous signal is still in existence. For this purpose, the present invention provides a novel mechanical selector or operating unit capable of translating the decoded signal into an actuating output of longer term.

Accordingly, the primary object of this invention is to provide a novel operating mechanism for recirculating matrix type-setting machines wherein input signals identifying individual matrices to be selected are accepted, in a sequence which may be irregular, and are translated into regularly timed outputs whereby the matrix release mechanisms are operated in the proper selected order and at regular intervals.

Another object of the invention is to provide such apparatus wherein the input identifying matrices to be selected are received in coded form, are decoded to identify the particular individual matrices desired, and wherein the decoded output is expanded and regularized in time to release the matrices in proper selected order and in a regular sequence which minimizes jamming and/or assembling of the matrices out of proper order.

A further object of the invention is to provide a control unit for a recirculating matrix typesetting machine which can operate from a coded input identifying the matrices in the order in which they are to be assembled, and which is capable of effecting release of the matrices at an opti-

2

mum and regular rate, in the proper order, and thereby to operate the typesetting machine at optimum speed.

An additional object of the invention is to provide such an operating unit for a typesetting machine which has a regular timed cycle of operations, including a portion of the cycle during which the coded input is received and decoded, and including another portion of the cycle overlapping the decoding portion and during which a power driven output is provided to operate the selected matrix release mechanism identified during the decoding operation.

Another object of the invention is to provide such an operating unit which is of simplified construction, incorporating easily manufactured parts which can readily and easily be made to within the tolerances necessary for proper functioning of the unit.

Other objects and advantages of the present invention will become more apparent from the following description, the appended claims and the accompanying drawings.

In the drawings:

FIG. 1 is a schematic diagram illustrating a typical coded input arrangement for apparatus in accordance with the invention;

FIG. 2 is a vertical sectional view taken through the decoding and operating device in accordance with the invention, showing one reed raised to select a matrix, and showing in dotted lines the position of the parts preparatory to raising the reed;

FIG. 3 is an enlarged detail view showing the stack of decoding strips, as indicated, in FIG. 2;

FIG. 4 is a view similar to FIG. 2, showing the parts in a rest position in full lines, and in a triggered position in dotted lines;

FIG. 5 is a schematic diagram illustrating the general form of construction of the decoding tapes or strips forming a part of the electro-mechanical decoding mechanism; and

FIG. 6 is an elevational view, with some parts broken away and shown in section, illustrating the manner in which the position of the decoding tapes are controlled by selectively energized solenoids.

Referring to the drawings, which illustrate a preferred embodiment of the present invention, in FIG. 1 a perforated tape reader is shown schematically at 10, and a typical perforated tape 12 is shown. As an example, this tape can be the well-known Teletypesetter or TTS tape used presently to control typesetting machines. The reader may be of any known type, and its output is directed into a decoder circuit, details of which will vary somewhat with respect to the type of reader employed. Various forms of decoder circuits are known, and the details thereof are not important herein. It will be sufficient for an understanding of the present invention to know that the decoder should be capable of receiving, for example, the six digit or six "bit" input from the reader 10 and translating this into a seven digit output, represented by the seven line cable 18 as illustrated.

Alternatively, the input to the apparatus can be derived from a keyboard 22 having incorporated therein a suitable form of encoding apparatus, which can provide a seven digit coded output identifying each key in the order in which the keys are struck. This output is represented in FIG. 1 by the seven line cable 24.

The cables 18 and 24 are directed into suitable buffer circuits, for example a plurality of OR gates which are shown schematically at 25, and the seven outputs from these gates are directed into a shift register circuit, illustrated as the seven flip-flop stages A1-A7, the functioning of which is controlled by a shift pulse input circuit 28. This circuit receives and transmits the shift control pulses from an amplifier 30 through the circuit line 32.

The various stages of the shift register are connected to control the energizing or deenergizing of seven solenoids 40a-40g, and these solenoids control corresponding crank levers 45a-45g (shown generally in FIG. 6) which in turn control the position of seven mechanical decoding strips or tapes 50a-50g. Each strip thus will assume one of two positions, corresponding to the energized or deenergized condition of its associated solenoid. Details of these decoding strips are more fully described later in this specification.

As is well known, typesetting machines of the circulating matrix type employ a matrix release mechanism for each channel, and normally this mechanism is some form of an escapement arranged to release a single matrix from the corresponding channel into assembling apparatus of the typesetting machine. Each such escapement mechanism may conveniently be operated by an actuating reed, one of which is indicated at 52 in FIGS. 2 and 4. The arrangement of such reeds and escapements is shown, for example, in United States Patent No. 3,042,188.

In accordance with the invention movement of one of these reeds is caused by the electro-mechanical decoding apparatus, the mechanical portion of which derives its power from a rotatably driven shaft 55. This shaft is, during normal operation of the machine, driven continuously at a constant speed, and one revolution thereof is considered to be one cycle of operation of the machine, during which one character matrix can be released.

This shaft also drives a conventional "light chopper" arrangement (or some equivalent pulse generator) provided by a continuously illuminated lamp 60, a photocell 62, and a rotatable disc 65 therebetween which rotates with shaft 55. This disc preferably is opaque and has a transparent slit 66 therein arranged to pass light to the photocell once for each revolution of the disc. The resultant pulse generated by photocell 62 is transmitted to amplifier 30, as shown in FIG. 1, thus establishing a pulse rate of one per cycle of operation.

Electro-mechanical decoder

The seven digit code output through cable 18 passes into the shift register and is set up in the control solenoids 40a-40g, which in turn control the position of seven decoding tapes or strips 50a-g. These strips extend the full width of the machine, beneath all of the reeds 52, recalling that there is one such reed for each escapement, and hence for each channel arranged to supply a character matrix, or space band or thin space, in other words any recirculatable member which can be assembled in forming a line of composition. These strips can be of any suitable thin material (such as thin stainless steel) having desirable long life wear characteristics.

These strips are provided with decoding perforations or holes (FIG. 5) arranged such that under normal conditions there is no open path through the stack of strips at any position corresponding to any reed 52. A typical cross-sectional view on an enlarged scale through the stack of strips is shown in FIG. 3, and at this particular section, chosen merely for purposes of example, there are passages through strips 50a through 50e, while there is no passage through strips 50f and 50g. It is assumed that in this condition all of the solenoids 40a-g are deenergized, and the strips are in what may be termed their "zero" position. If the code 0000011 appears in the "shift" register, then solenoids 40f and 40g will be energized and the corresponding strips 50f and 50g will be shifted, and in this shifted position they will present passages therethrough in the location shown in FIG. 3. This may be decoded as the selection code for the letter "T" (i.e. 0000011). In like fashion, at a position corresponding to each reed 52, there will be a passage presented through all of the decoding strips whenever the

75 solenoids position these strips according to the code for the character which is related to that reed.

For each reed there is a corresponding trigger member 100, which is adapted to raise its reed when the proper selection code is presented. In its normal position, the trigger member rests upon a support bar 105, all of the triggers being stacked in parallel relation, beneath their corresponding reeds. A finger 106 is provided on the trigger member to assure that whenever it is raised it always is returned to the normal or rest position as shown in full lines in FIG. 4. The support bar 105 is stationary, being fastened by screws 107 to a part of the supporting frame of the decoding controller. It will be understood that the reeds 52 are all normally in a lowered position, as shown in FIG. 4, and in such position each reed is suspended over a corresponding finger 110 of its trigger member 100, with a slight clearance therebetween.

Another section 112 of the trigger extends outward with respect to bar 105, and a return spring 113 is fastened between this portion of the trigger and a stationary bracket 114 on a lower part of the frame. Farther out on the finger portion 112 of each trigger there is a depending sensing finger 115 which rests upon the stack of tapes 50a-50g. In the normal position this sensing finger rests upon that uppermost one of the tapes which normally present an obstruction. The outward extending finger 112 continues beyond the sensing finger portion, and preferably is bent downwardly and outwardly to form a lifting end 120 which projects beyond the stack of decoding tapes, as shown in the drawing.

Mechanical controller

During a predetermined portion of each cycle of operation of the machine a set-up lever 122 is swung counterclockwise, as viewed in FIGS. 2 and 4 around its pivot mount 123. This raises the set-up bar 125 into engagement with the lifting ends 120 of all of the triggers 100. The limit of such lifting motion of the set-up bar can be seen from comparison of FIGS. 2 and 4, the bar being shown approximately in its fully raised position in FIG. 2, and approximately in its lowermost position in FIG. 4.

Immediately below the lever 122 there is a pivotally mounted bail lever 130, mounted to swing about a pivot stud or pin 132. This lever is connected to the lever 122 by an arm 134, there being pivotal connections at each end of this arm, as indicated by the pins 135. The drive for reciprocating both of the levers 122 and 130 is obtained from an eccentric 140 fastened to shaft 55, and arranged to produce a generally reciprocating motion in a crank rod 142 which is pivotally connected through pin 143 to the bail arm 130.

At the end of the arm 130 is mounted the bail bar 145, which extends the full width of the machine so as to be positioned beneath each of the depending lifting finger 147 formed on each of the triggers 100. In order to assure lifting engagement when this is desired, a keeper bracket 148 extends along the face of the bail bar 145.

Also driven from shaft 55 is a control cam 150 which engages a roller follower 152 carried on the lower end of a driver lever 155. This lever is mounted for pivotal movement on the frame, by means of a pivot stud or shaft 156, and at the upper end of lever 155 there is a slotted reed control bar 158 which likewise extends the full width of the machine and around all the reeds so as to engage any reed which might be positioned in its path of movement. Immediately below this bar 158 there is a stationary shelf 160, formed by the top edge of a bar 162 fastened to the frame.

The operation may be briefly described as follows. The appropriate lever 100 is placed in a cocked or active position by movement of its sensing finger 115 through a complete aperture presented to it by appropriate movement of the decoding tapes. When this oc-

curs, the selected trigger will drop from the full line to the dotted line position shown in FIG. 4, and this motion is assisted by the corresponding spring 113.

The light chopper disc 65 is preferably positioned on shaft 55 such that the electronic timing pulse from photocell 62 occurs just before the top dead center position of the eccentric 140. This relationship is indicated in FIG. 2, and it will be noted that the shaft 55 is arranged to rotate counterclockwise as viewed. When the eccentric reaches its bottom dead center position all of the trigger members 100 will be resting upon the stationary supporting bar 105, as shown in FIG. 4.

Before the eccentric has passed through this approximately 180° of travel, a pulse from amplifier 30 will have passed to the shift register gate 28, and the code for the next character to be selected will be set up in the register, and this in turn will energize appropriate ones of the solenoids 40a-40g. Therefore, somewhere along the tapes there will be one through passage presented to a sensing finger 115.

This finger will drop through such aperture and the finger will move to its cocked or ready position shown in dotted lines in FIG. 4. All other triggers will assume the position shown in full lines in FIG. 4. Then as the eccentric produces a lifting motion in the crank rod 142 both the set-up bar 125 and the bail bar 145 will begin to rise. The mechanical relationship is such that the bail bar will engage the drive finger 147 of the cocked trigger, as shown in the dotted position in FIG. 4. Simultaneously, the set-up bar 125 will engage the outer end 120 of that trigger, and as the bail bar continues upward it will lift the cocked trigger, with the motion being essentially a direct vertical motion, since both the bail bar and the set-up bar are lifting upward on different portions of the trigger at the same time. All of the drive fingers 147 of the other triggers will be in the solid line position in FIG. 4, and the bail bar will pass to one side of them.

Accordingly, the selected trigger 100 will move upward carrying its reed 52 upward, as shown in solid lines in FIG. 2. This trigger will lift away from the stationary supporting bar 105. The lower end of reed 52 will be carried up to a position slightly above the shelf 160, as shown in FIG. 2. At the same time the reed control bar 158, which also has an actuating function, will move to the left as viewed in FIG. 2, since the cam roller 152 will be following cam 150 as shown in FIG. 2. Therefore, the portion 165 of bar 158 will engage the lifted reed and slide it over the shelf 160, and the reed will drop onto this shelf as the eccentric 140 passes over its top dead center position and the corresponding trigger begins to descend.

In this fashion, the reed is actually caused to pause momentarily in its raised position, assuring that it produces an effective release action of the escapement to which it is connected.

It will be noted from FIG. 2 that the set-up bar 125, as it rises, will not only carry the cocked or operative trigger 100 upward, but also it will engage the outer end portions 100 of all the triggers, lifting all sensing fingers 115 away from the tapes during the portion of the cycle in which the next selection code is being set up in the tapes.

It will be apparent from FIGS. 2 and 4 that each of the reeds 52 is provided with a notch 167. All the reeds except the one which has been selected will present this notch in the path of movement of the control bar portion 165 as it moves inward to set the selected reed upon the shelf. This inward motion commences as the peak of cam 150 passes beyond the roller 152, and this occurs at approximately 45° before the top dead center position of the eccentric 140. Then, as can be seen from FIG. 4, at about 300° to 310° after the top dead center position of the eccentric, the cam 150 begins to lift the roller 152, and the reset bar 158 moves to the right,

as viewed in FIG. 4, and it will engage the raised operative reed and push it off the shelf 160.

From the foregoing description it will be apparent that the present invention provides a quick acting, positive, and regularly timed or cycled control for typesetting machines or like apparatus. The timing of operation of the reeds, which transmit power to the character releasing mechanisms, is dependant upon the regular driving movement of the bail member. Furthermore, the electro-mechanical decoding apparatus is quick acting and positive, since the solenoids can be operated rapidly in response to energization or de-energization of their coils. This action, together with the perforated tapes or strips controlled by the solenoids, provides only one release opening or passage for the selected trigger member, such that the decoding operation is rapid and positive, and only one trigger member can be actuated for any given code.

The operating unit also provides for direct, regular, and rapid operation of the typesetting machine from a coded input, and this input may be derived from conventional perforated tape records or equivalent, or from a keyboard with a suitable encoding arrangement by means of which the operation of a key can be transmitted to the electro-mechanical decoding device as a coded signal. This permits the keyboard to be located remotely from the actual typesetting machine, while still being directly coupled thereto. An operating unit as disclosed herein also is advantageous from the standpoint of simplicity of design, for the purpose of manufacture and maintenance. The parts required can readily be machined, and in the case of the trigger members particularly, they can be manufactured with proper accuracy as relatively inexpensive stampings.

While the form of the apparatus herein described constitutes a preferred embodiment of the invention, it is to be understood that the invention is not limited to this precise form of apparatus, and that changes may be made therein without departing from the scope of the invention which is defined in the appended claims.

40 What is claimed is:

1. In a typesetting machine having at least one magazine with a plurality of channels each adapted to hold like matrices for individual characters and including releasing mechanism associated with each channel for releasing a single matrix therefrom into an assembler, an operating reed for each said releasing mechanism arranged to transmit actuating power thereto; the improvement comprising a bail member, a drive for said bail member operative to reciprocate said bail member in a cyclic manner along a predetermined path of movement, a plurality of trigger members, one for each of said reeds, each of said trigger members having a bail engaging portion and a reed engaging portion for forming a drive connection between said bail member and the associated reed; means supporting all of said trigger members with the bail engaging portions thereof normally aligned out of said path of said bail member and with said reed engaging portions thereof in alignment with the associated said reeds, decoding means operative on said trigger members to cause movement of one of said trigger members according to a selective code input to said decoding means to shift the position of a selected one of said trigger members into an actuating position bringing the bail engaging portion of the selected trigger member into said path of movement of said bail member whereby motion of said bail member is transmitted through the so-moved trigger member to a single selected reed.

2. In a typesetting machine having at least one magazine with a plurality of channels each adapted to hold like matrices for individual characters and including releasing mechanism associated with each channel for releasing a single matrix therefrom into an assembler, an operating reed for each said releasing mechanism arranged to transmit actuating power thereto; the improvement comprising a bail member, a drive for said bail

member operative to reciprocate said bail member in a cyclic manner along a predetermined path of movement, a plurality of trigger members, one for each of said reeds, each of said trigger members having a bail engaging portion and a reed engaging portion for forming a drive connection between said bail member and the associated reed, each of said trigger members also having a control portion for locating its said bail engaging portion with respect to the path of movement of said bail member, means supporting all of said trigger members with the bail engaging portions and control portions thereof normally aligned and with said reed engaging portions thereof in alignment with the associated said reeds, and decoding means operative on said control portions to cause movement of one of said trigger members according to a selective code input to said decoding means to shift the position of a selected one of said trigger members into an actuating position bringing the bail engaging portion of the selected trigger member into said path of movement of said bail member whereby motion of said bail member is transmitted through the so-moved trigger member to a single selected reed.

3. In a typesetting machine having at least one magazine with a plurality of channels each adapted to hold like matrices for individual characters and including releasing mechanism associated with each channel for releasing a single matrix therefrom into an assembler, an operating reed for each said releasing mechanism arranged to transmit actuating power thereto; the improvement comprising a bail member, a drive for said bail member operative to reciprocate said bail member in a cyclic manner along a predetermined path of movement, a plurality of trigger members, one for each of said reeds, each of said trigger members having a bail engaging portion and a reed engaging portion for forming a drive connection between said bail member and the associated reed, each of said trigger members also having a control portion for locating its said bail engaging portion with respect to the path of movement of said bail member, means supporting all of said trigger members with the bail engaging portions and control portions thereof normally aligned and with said reed engaging portions thereof aligned with the associated said reeds, decoding means operative on said control portions to cause movement of one of said trigger members according to a selective code input to said decoding means to shift the position of a selected one of said trigger members into an actuating position bringing the bail engaging portion of the selected trigger member into said path of movement of said bail member whereby motion of said bail member is transmitted through the so-moved trigger member to a single selected reed, and means operating in timed relation to said bail member for holding the moved reed in its actuated position for a time period substantially in excess of the driving movement of its associated trigger member.

4. In a typesetting machine having a magazine with a plurality of channels for holding matrices, including releasing mechanism associated with each channel for releasing a single matrix therefrom, and an operating reed for each said releasing mechanism; the improvement comprising a bail member, a drive for said bail member operative to reciprocate said bail member in a cyclic manner along a predetermined path of movement, a plurality of trigger members, one for each of said reeds, each of said trigger members having a bail engaging portion and a reed engaging portion for forming a drive connection between said bail member and the associated reed, each of said trigger members also having a control portion for locating its said bail engaging portion with respect to the path of movement of said bail member, means supporting all of said trigger members with the bail engaging portions and control portions thereof normally aligned and with said reed engaging portions thereof aligned with the associated said reeds, means acting on the individual said trigger member urging said bail engaging portions to-

ward said path of said bail member, decoding strips engaging said control portions to hold said trigger members in said normal aligned relation, and means connected to move at least one of said strips according to a selective code to release a selected one of said trigger members into an actuating position wherein its bail engaging portion is moved into said path of movement of said bail member and motion of said bail member is transmitted through the so-moved trigger member to a single selected reed.

5. In apparatus of the character described the combination of a plurality of operating reeds each adapted to transmit mechanical power by a longitudinal movement thereof, a bail member, drive means for moving said bail member along a predetermined path, and a plurality of trigger members, one for each of said reeds, adapted to form a selective drive connection between said bail member and the associated said reed, means supporting said trigger members in a normally inoperative position removed from said path of movement, said supporting means including a control portion on each of said trigger members, a plurality of decoding tapes having holes selectively placed therein according to a selector code, means supporting said tapes in stacked relation adjacent said control portions such that in a normal position at least one of said tapes is engaged with said control portions to hold said trigger members in the inoperative position, and means for moving at least one of said tapes in accordance with a selection code to present a continuous opening through the stacked tapes to a selected one of said control portions whereby the associated trigger member is moved into said path of movement of said bail member to form a power transmitting drive between said bail member and the reed associated with the selected trigger member.

6. In apparatus of the character described the combination of a plurality of operating reeds each adapted to transmit mechanical power by a longitudinal movement thereof, a bail member, drive means for moving said bail member along a predetermined path, and a plurality of trigger members, one for each of said reeds, adapted to form a selective drive connection between said bail member and the associated said reed, means supporting said trigger members in a normally inoperative position removed from said path of movement, said supporting means including a control portion on each of said trigger members, a plurality of decoding tapes having holes selectively placed therein according to a selection code, means supporting said tapes in stacked relation adjacent said control portions such that in a normal position at least one of said tapes is engaged with said control portions to hold said trigger members in the inoperative position, means urging said control portions toward said tapes, and solenoid means connected to each of the individual said tapes for shifting the associated tape between one of two positions corresponding to binary code information supplied to the solenoids as energizing and deenergizing power in accordance with a selection code to present a continuous opening through the stacked tapes only to a selected one of said control portions permitting the associated trigger member to move into said path of movement of said bail member to form a power transmitting drive between said bail member and the reed associated with the selected trigger member.

7. In apparatus of the character described the combination of a plurality of operating reeds each adapted to transmit mechanical power by a longitudinal movement thereof, an elongated bail member, drive means for moving said bail member along a predetermined path, a plurality of trigger members, one for each of said reeds, adapted to form a selective drive connection between said bail member and the associated said reed, means supporting said trigger members in side-by-side relation in a normally inoperative position to one side of and out of said path of movement, said supporting means including a control portion on each of said trigger members, a plural-

ity of tapes having holes selectively placed therein according to a selection code, means supporting said tapes in stacked relation parallel to said bail member and adjoining said control portions such that in said inoperative position at least one of said tapes is engaged with said control portions to hold said trigger members in the inoperative position, and means for moving different ones of said tapes in accordance with a selection code identifying one of said reeds to present a continuous opening through the stacked tapes to the control portion of the selected one of said trigger members permitting such trigger member to move into said path of movement of said bail member to form a power transmitting drive between said bail member and the reed associated therewith.

8. In a typesetting machine having a magazine with a plurality of channels for individual character matrices and including releasing mechanism associated with each channel for releasing a single matrix therefrom, an operating reed for each said escapement mechanism arranged to transmit actuating power to the associated escapement mechanism; the improvement comprising a continuously rotating drive shaft and means for rotating said shaft at a predetermined constant speed, a bail member extending beneath all of said reeds, a drive connection between said shaft and said bail member for moving said bail member along a predetermined path of movement toward and away from said reeds, a plurality of trigger members, cor-

responding in number to said reeds, each of said trigger members having a bail engaging portion and a reed engaging portion normally contacting the associated reed for forming a drive connection between said bail member and the associated said reed, each of said trigger members also having a control portion for locating its said bail engaging portion with respect to the path of movement of said bail member, means supporting all of said trigger members in a normal inoperative position, decoding means operative on said control portions to cause movement of one of said trigger members corresponding to a selection code input to said decoding means to shift the position of a selected one of said trigger members into an actuating position bringing its bail engaging portion into the said path of movement of said bail member whereby motion of said bail member is transmitted through the so-moved trigger member to its associated reed.
